UNITED STATES PATENT OFFICE.

JOHN DOYLE, OF NEW YORK, N. Y.

DESIGN FOR A SHADE, REFLECTOR, OR SIMILAR ARTICLE FOR A LIGHTING-FIXTURE.

59,201.

Specification for Design.

Patented Oct. 4, 1921.

Application filed February 5, 1921. Serial No. 442,838. Term of patent 14 years.

To all whom it may concern:

Be it known that I, JOHN DOYLE, a citizen of the United States, residing at New York, Bronx county, State of New York, have invented a new, original, and ornamental Design for Shades, Reflectors, or Similar Articles for Lighting-Fixtures, of which the following is a specification, reference being had to the accompanying drawing, forming part thereof.

The figure is an elevation of a lighting fixture, showing my new design.

As illustrated, it consists of two reflectors, the narrower end of one extending within the wider end of the other. The reflector marked 1 has an outer wall that is convex, the outer wall of the one marked 2 being concave. They are fastened together in any desired way.

I claim:

The ornamental design for a shade, reflector or similar article for a lighting fixture, as shown.

JOHN DOYLE.
